UNITED STATES PATENT OFFICE.

EDSON F. GALLAUDET, OF EAST GREENWICH, RHODE ISLAND.

TENNIS AND SIMILAR RACKET.

Application filed July 18, 1923. Serial No. 652,214.

To all whom it may concern:

Be it known that I, EDSON F. GALLAUDET, a citizen of the United States, residing at East Greenwich, in the county of Kent and 5 State of Rhode Island, have invented certain new and useful Improvements in Tennis and Similar Rackets, of which the following is a specification.

My present invention relates to tennis and 10 similar rackets, and, specifically, to a protective reinforcement or bull's-eye for the strings thereof.

In the case of rackets strung with gut, 15 the stringing rarely has opportunity to wear out, but usually fails through a snapping of a string or of several strings, at one point or another indeterminately, due to some inherent defect in the gut or to the effect of atmospheric moisture.

20 Strings of silk or other similar fiber, however, when made according to an earlier invention of mine, are moisture proof and will last, and retain their tension, until worn out. The wear is confined almost wholly to 25 what may be called the crests of the strings, where they are bulged outwardly in crossing one another and where primarily they come into contact with the ball; and, while the strings of rackets used by players of 30 average skill will last for a long time, in the hands of experts, who always hit hard and very accurately, the wear on the strings at the center of the head may be quite rapid, particularly if the play is on a clay or dirt 35 court where the grit picked up by the ball acts as an abrasive.

I have discovered that by lacing the strings 40 through the central portion of the head with an extra cord, which can be renewed as often as required, so as to wrap and cover their crests on both sides of the racket, I can for all practical purposes entirely eliminate the 45 wear of the strings and so prolong their life indefinitely. Furthermore, such extra 50 wrappings not only firmly secure the strings together at their crossings, rendering unnecessary the extra cord often woven across the strings to hold them in place, but also serve to grip the ball in cut or chop strokes 55 and hence are effective in imparting an extra spin to the ball in strokes where spin is desired.

The invention will be understood by reference to the accompanying drawing, 55 wherein—

Fig. 1 is a side view of the head of a

racket showing more or less diagrammatically the strings and the extra wrappings which form the protective bull's-eye, and Figs. 2 and 3 are enlarged details showing the wrappings as they appear in the form preferred on the two opposite sides of the racket, respectively.

As here illustrated the extra cord *a* with which the square protective bull's-eye is 60 formed, is so laced about the strings as to protect their crests at the crossings with a double wrapping on one side of the racket (Fig. 2), while, on the other side (Fig. 3), the single wrapping which passes directly 65 over the crest of each string is supplemented by slightly lower wrappings on each side. In this way a wrapping is provided which affords approximately the same amount of 70 actual wearing surface on each face of the 75 racket.

The cord used for the protective wrappings may be of any suitable material. Wire 80 has been tried with good results, and gut may be used if desired; but, as at present advised, I prefer and recommend the ordinary enamelled braided silk lacing cord regularly used for the "rough and smooth" 85 lacings at the point and throat of rackets.

It will also be found advantageous to apply to the wrappings of extra cord the same 90 spar varnish or similar composition with which I impregnate and coat my silk strings, as by dipping the entire head of the racket in the varnish, thus binding the wrappings 95 to the strings and rendering both alike waterproof.

While of special value for use with silk 95 or other fiber strings, it is to be understood that the invention is not limited to use therewith but is applicable to any kind of stringing.

What I claim as new, and desire to secure by Letters Patent, is—

1. A tennis or similar racket having its 100 stringing protected against wear by a cord which, throughout the central portion of the racket head, is laced about the strings at their crossings in manner to cover the crests of both strings.

2. A tennis or similar racket having the 105 crests of its strings protected from wear through the central portion at least of the racket head by a double wrapping of cord on one side of the racket and on the other side by a single wrapping flanked on each side by a somewhat lower wrapping.

3. A tennis or similar racket which has its strings laced with extra cord to provide protective wrappings on the crests of the strings at their crossings through the central portion at least of the racket head and which has a waterproofing composition applied to both strings and wrappings.
4. A tennis or similar racket strung with thoroughly stretched fiber strings which through the central portion at least of the racket head are protected from wear at their crossings by wrappings of extra cord

and are rendered waterproof by the application to both strings and wrappings of a suitable waterproofing composition.

5. A tennis or similar racket strung with thoroughly stretched silk strings which at their crossings through the central portion at least of the racket head are protected from wear by wrappings of extra cord and are impregnated and coated with a hard drying waterproofing composition.

EDSON F. GALLAUDET.
